UNITED STATES PATENT OFFICE.

CHARLES C. GATES, OF DENVER, COLORADO, ASSIGNOR TO THE INTERNATIONAL RUBBER COMPANY, OF DENVER, COLORADO, A CORPORATION OF COLORADO.

DESIGN FOR A TIRE-TREAD.

49,645.

Specification for Design. Patented Sept. 12, 1916.

Application filed March 13, 1916. Serial No. 83,980. Term of patent 3½ years.

To all whom it may concern:

Be it known that I, CHARLES C. GATES, a citizen of the United States, residing in the city and county of Denver, State of Colorado, have invented a new, original, and ornamental Design for Tire-Treads, of which the following is a specification, reference being had to the accompanying drawing, forming a part hereof.

In this drawing, Figure 1 is an elevation of a tire tread, showing my new device. Fig. 2 is a fragmentary view of the same

shown on a larger scale. Fig. 3 is a section taken on the line 3—3, Fig. 2.

I claim.—

The ornamental design for a tire tread as shown.

In testimony whereof I affix my signature, in presence of two witnesses.

CHARLES C. GATES.
